CLAIM

The ornamental design for a device for a personal emergency response system, as shown and described.

DESCRIPTION

FIG. 1 is a top, front, left perspective view of a device for a personal emergency response system, showing our new design;

FIG. 2 is a top, front, right perspective view thereof;

FIG. 3 is a front view thereof;

FIG. 4 is a right side view thereof;

FIG. 5 is a rear view thereof;

FIG. 6 is a left side view thereof;

FIG. 7 is a top view thereof;

FIG. 8 is a bottom view thereof;

FIG. 9 is a bottom, front, left perspective view thereof; and, FIG. 10 is a bottom, front, right perspective view thereof. The shade lines show surface contour and not surface ornamentation.

The broken lines depict portions of the device for a personal emergency response system that form no part of the claimed design.

1 Claim, 10 Drawing Sheets
